UNITED STATES PATENT OFFICE.

OLAF M. HAMMER, OF OAKMONT, PENNSYLVANIA.

MECHANICAL TOY.

1,183,643.

Specification of Letters Patent.

Patented May 16, 1916.

Application filed October 14, 1914. Serial No. 866,595.

To all whom it may concern:

Be it known that I, OLAF M. HAMMER, a citizen of the United States, residing at Oakmont, in the county of Allegheny and 5 State of Pennsylvania, have invented certain new and useful Improvements in Mechanical Toys of which the following is a specification.

My invention relates to improvements in 10 game apparatus and more particularly to apparatus of the automatic type.

The objects of my invention are to provide an apparatus which is simple in construction, which is amusing, which combines 15 simple and efficient mechanism for providing the operation, and which can be manufactured at a relatively low cost.

To these and other ends, the nature of 20 which will be readily understood as the invention is hereinafter disclosed, said invention consists in the improved construction and combination of parts hereinafter fully described, illustrated in the accompanying drawings, and more particularly pointed 25 out in the appended claims.

In the accompanying drawings, in which similar reference characters indicate similar parts in each of the views, Figure 1 is a front elevation of the apparatus in position to operate; Fig. 2 is a side elevation of the same; Fig. 3 is a plan view showing the delivery structure of the apparatus; Fig. 4 is a detailed sectional view taken on line 4—4 of 30 Fig. 3; Fig. 5 is a top plan view of one of 35 the cars; Fig. 6 is a cross section taken on line 6—6 of Fig. 2; and Fig. 7 is a detailed sectional view taken on line 7—7 of Fig. 1.

The apparatus herein disclosed simulates, 40 to some extent, the operations of inclined railways in use in various cities, and in which the general structure includes a pair of cars adapted to be connected together in a manner to travel in opposite directions along the inclined track, these cars being 45 adapted to carry fixed loads of various types. In the present invention, the cars are adapted to carry the load only in a downward direction, the load providing the power for manipulating the cars or carriages, means being provided for automatically 50 positioning the load on one of the cars as the other car automatically discharges the load which formed the power in bringing

the load receiving car into position. The load, in the present apparatus, is preferably 55 in the form of a spherical body, such for instance, as a marble.

The track portion of the apparatus is formed from a plate 10, preferably of sheet metal and having a cross section substantially as shown in Fig. 6 in which a central depression 10^a, extending lengthwise of the plate, cooperates with two marginal depressions 10^b extending parallel to the central depression, to provide tracks for a pair of 60 cars, the material between these depressions forming guides to retain the cars against lateral movement.

The plate is adapted to be supported in an inclined position by reason of a lower sheet 70 metal arm 11 and a supporting member 12 swingingly carried by the edges of the plate at a point near the upper end of the plate, said support being somewhat in the nature of a bail expanded at its lower end having 75 the lower cross connecting portion formed with a bend 12^a adapted to engage a hook 11^a struck up from the arm 11, said arm being pivoted to the lower end of the plate, thus permitting the track structure to 80 be collapsed for packing purposes when desired; the arm 11, when the structure is in operating position forms the base on which the entire apparatus is supported, the bail engaging with the arm and the plate to retain 85 the track in its proper inclined position.

The upper end of the plate is provided with a central opening 13 which is adapted to receive a wheel supporting member 14, 90 the latter being adapted to receive a peripherally grooved wheel 15, the general arrangement being more particularly shown in Fig. 7. The upper end of the plate is also provided with ears 16 and 17 formed by 95 slitting the plate, these ears being adapted to support the delivery apparatus shown more particularly in Fig. 3, and consisting of a load container in the form of a plate 18 having a cut-away portion 18^a, the plate carrying curved portions 18^b at opposite sides of this cut-away portion, said curved portions forming delivery chutes for the loads, said chutes extending forwardly a suitable 100 distance and being adapted to be controlled 105 by gates 19. The plate 18 is preferably pro-

vided with a marginal flange 18^c and also with an upwardly projecting division portion 18^a, the latter acting as a marginal flange for one side of the cut-away portion 18^b. The plate 18 is preferably bulged upwardly at its center, thus providing sloped portions which are adapted to direct the loads toward the end of the plate.

As shown in Fig. 2, the plate 18, when the apparatus is in operation, is inclined upwardly and as the flanges 18^c and 18^a serve to provide run-ways for the loads extending in directions leading first toward the ends of the plate and then inwardly toward the chutes, it will be readily understood that a number of loads in the form of marbles or other spherical bodies may be indifferently placed upon the plate on opposite sides of the bulge from where they will travel to the chutes successively through the run-ways.

As will be seen more particularly in Fig. 3, the load run-ways lead into the delivery chutes at substantially right angles to the direction of length of these chutes, the result being that the pressure of the loads in the supply and the runways is not exerted in the direction of length of the chutes but rather in directions to intersect the direction of length of the chute. Consequently, the loads which may be in the chute and which are subjected to the control of the gate mechanism are not affected by this pressure. As a result, the gate control mechanism is subject to the pressures only of a few loads regardless of the number of loads which may be within the supply, and consequently, such mechanism may be of the simple form disclosed herein and yet be free from damage; furthermore, this absence of pressure from the runway practically permits the segregation and delivery of the loads one by one.

The gate structure is of simple form, shown more particularly in Figs. 3 and 4, being simply in the form of a curved plate 19^a having a rod 19^b adapted to be mounted in ears 18^c of the chutes, the plate being provided with a forwardly extending arm 19^c, the latter carrying a stop 19^d which is adapted to rest upon the vertical walls of the chute when in normal position. The plate 19^a is preferably cut-away as at 19^e. As shown in Fig. 4, it will be understood that the plate 19^a will, when the arm 19^c is in its lower or normal position, act to prevent the marble (indicated at 20) from passing downward through the chute. If the plate 19^a be moved on its pivot by raising the arm 19^c, the marble which is in contact with the plate will be released, and the rear portion of the plate will pass into the path of travel of the succeeding marble and thus prevent the latter from passing into discharging position until the plate has again resumed its normal position. This arrange-

ment provides a simple and efficient feeding apparatus formed mainly of sheet metal. The plate 18 is preferably compressed by means of sheet metal braces 21, as shown in Fig. 2.

23 designates a car preferably formed of sheet metal and having sides 23^a and a top curved inwardly as at 23^b. The car is supported by wheels 24 of simple form, the latter being adapted to extend into the depressed portions of the track. As shown more particularly in Fig. 2, the car is generally triangular in shape in side elevation, the curved portion having its direction of length inclined downwardly toward the front of the car, the inclination being sufficient to permit the marble to roll forward in being discharged from the car.

The car is provided with a swinging device, formed of light material such as wire 85 and indicated at 26, said device being pivoted at the rear of the curved portion of the car and extending forwardly, a curved portion 26^a lying normally in the path of travel of the marble over the curved face. 90 The swinging member is provided with a forwardly projecting arm 27, this arm being adapted to coact with a vertically extending member 28 carried by the plate 10, said latter member having laterally projecting arms 28^a which extend into the path of travel of the arm 27, the arrangement being such that as the car descends, the arm 27 is brought into contact with one of the parts 28^a, the result being that as the car continues its descent, the member 26 is swung on its pivot and thus carries the curved portion 26^a out of its marble-holding position and permits the marble to pass off the car. The car is also provided with a fixed upwardly projecting member 29 having a laterally projecting portion 29^a which forms the operating element for moving the gate 19 to release a marble, this action taking place as the car approaches the ends of its upper travel, the laterally projecting portion 29^a passing into contact with the arm 19^c, raising the latter and moving the plate 19^a on its pivot.

The cars are connected by a suitable flexible member such as a cord or wire 30, the latter having its ends connected to the cars and passing around the wheel 15, the flexible member 30 being of such length that the marble will be released from the lower car at the time when the arm 29^a has raised the arm 19^c a distance sufficient to permit the discharge of a marble from the chute, this arrangement being provided in order that the weight of the marble on the descending car will continue for the length of time sufficient to insure that the marble which forms the succeeding load is released.

The operation of the apparatus is simple and readily understood from the drawings.

A number of marbles are placed on the plate 18 so as to pass into the opposite runways, and the cars manipulated so as to bring one of them into contact with and 5 raise the arm 19^e of the gate with which it co-operates. This releases a marble which then rolls from the chute on to the car and into contact with the curved portion 26^a where it is retained. As the marble increases 10 the weight of the car, the loaded car will travel downwardly on its track, and through the connection of the flexible member 30, will cause the empty car to travel upwardly on the track. This movement of the loaded 15 car will continue until the raising of the arm 27 releases the marble of the loaded car, leaving the marble free to roll off the car. During the latter portion of the travel of the loaded car, the ascending car has caused 20 the gate of the other chute to be opened and thus release a marble from that chute on to the upper car, the latter in turn becoming the loaded car and reversing the operation. This operation will continue as along as 25 there is a marble in the chute of the ascending car, so that by employing a number of marbles, the cars will be caused to alternately travel up and down the incline and give a vivid showing of the action of the 30 inclined railway structures.

What I claim is:—

1. In mechanical toys and in combination, a sheet metal track structure formed to provide a pair of parallel tracks, a support for 35 positioning the structure with its direction of length inclined to the vertical and horizontal, a load receptacle at the upper end of said structure, independent load segregating and releasing means for discharging fixed 40 loads individually from the receptacle above the tracks, a pair of load carriers movable on said tracks and connected to move in opposite directions in unison, said carriers each having means for manipulating the load discharge mechanism of the receptacle and also having means for temporarily retaining 45 the load in position on the carrier, and means on the structure for releasing said load retaining means when each carrier reaches a predetermined position.

2. In mechanical toys and in combination, a sheet metal track structure formed to provide a pair of parallel tracks, a support for 55 positioning the structure with its direction of length inclined to the vertical and horizontal, a load receptacle at the upper end of said structure, independent load segregating and releasing means for discharging fixed 60 loads individually from the receptacle above the tracks, a pair of load carriers movable on said tracks and connected to move in opposite directions in unison, said carriers each having means for manipulating the load discharge mechanism of the receptacle and 65 also having means for temporarily retaining

the load in position on the carrier, and means on the structure for releasing said load retaining means when each carrier reaches a predetermined position, said latter means being located in the path of travel of 70 the load retaining means, whereby the travel of the carrier will automatically release the load.

3. In mechanical toys and in combination, a sheet metal track structure formed to provide a pair of parallel tracks, a support for 75 positioning the structure with its direction of length inclined to the vertical and horizontal, a load receptacle at the upper end of said structure, independent load segregating and releasing means for discharging fixed 80 loads individually from the receptacle above the tracks, a pair of load carriers movable on said tracks and connected to move in opposite directions in unison, said carriers each having means for manipulating the load discharge mechanism of the receptacle and also having means for temporarily retaining 85 the load in position on the carrier, and means on the structure for releasing said load retaining means when each carrier reaches a predetermined position, the movements of said carriers being timed to provide 90 the load releasing action on one carrier at approximately the time of load receiving 95 operation of the other carrier, whereby the load discharge from the descending carrier and the load receipt of the ascending carrier of the carriers.

4. In mechanical toys and in combination, an inclined track structure, a pair of connected load carriers adapted to travel thereon in opposite directions, a load receptacle at the upper end of the track and having 100 means for discharging individual loads to the carriers when the latter are in juxtaposition thereto, and load releasing means adjacent the bottom of the track, said discharging mechanism comprising a pair of chutes, 105 and a swinging gate in each chute, and having its axis extending at right angles to the direction of load travel through the gate, each gate being normally in position to prevent the escape of the load, each carrier having 110 means co-operating with the gate to swing the latter and discharge the load on to the carrier during the travel of the carrier to its upper position.

5. In mechanical toys and in combination, an inclined track structure, a pair of connected load carriers adapted to travel thereon in opposite directions, a load receptacle at the upper end of the track and having means for discharging individual loads to the carriers when the latter are in juxtaposition thereto, and load releasing means adjacent the bottom of the track, said discharging mechanism comprising a pair of chutes, and a swinging gate in each chute, and having 115 120 125 130

- 4
- its axis extending at right angles to the direction of load travel through the gate, each gate being normally in position to prevent the escape of the load, each carrier having means coöperating with the gate to swing the latter and discharge the load on to the carrier during the travel of the carrier to its upper position, said latter means embodying a fixed arm projecting above the carrier.
10. In mechanical toys, a load receiving element movable in one direction under the weight of the load, and means for segregating loads for and delivering loads to said element, said means comprising a load run-way, a pivoted gate in said run-way and having its pivot axis extending at right angles to the direction of length of the run-way and located above the path of movement of the load through said run-way, and complementary means carried by the carrier and said gate for moving the gate on its pivot to place it in load-delivering position and retain it in such position while the element is in load-receiving position, said gate having a configuration to act as a load-restraining element at either extreme of its pivotal movement.
15. In mechanical toys and in combination, an inclined track structure, a pair of connected load carriers adapted to travel thereon in opposite directions, a load receptacle at the upper end of the track and having means for discharging individual loads to the carriers when the latter are in juxtaposition thereto, load-retaining means on the carrier, and load releasing means adjacent the bottom of the track and adapted to coöperate with the carrier retaining means to release the load, said carrier having a fixed load receiving surface extending continuous from end to end of the carrier and inclined with respect to the track and to the horizontal.
20. In mechanical toys and in combination, an inclined track structure, a pair of connected load carriers adapted to travel thereon in opposite directions, a load receptacle at the upper end of the track and having means for discharging individual loads to the carriers when the latter are in juxtaposition thereto, load-retaining means on the carrier, and load releasing means adjacent the bottom of the track and adapted to coöperate with the carrier retaining means to release the load, said carrier being formed of sheet metal and having a depressed load receiving face extending continuous from end to end of the carrier and with the direction of length of the face inclined to the track and to the horizontal, and means on the carrier extending above said surface for temporarily retaining the load against discharge from said face.
25. In mechanical toys and in combination, an inclined track structure, a pair of connected load carriers adapted to travel thereon in opposite directions, a load receptacle at the upper end of the track and having means for discharging individual loads to the carriers when the latter are in juxtaposition thereto, load-retaining means on the carrier, and load releasing means adjacent the bottom of the track and adapted to coöperate with the carrier retaining means to release the load, said carrier being formed of sheet metal and having a depressed load receiving face extending continuous from end to end of the carrier and with the direction of length of the face inclined to the track and to the horizontal, and means on the carrier extending above said surface for temporarily retaining the load against discharge from said face, said latter means being automatically shifted to release the load when the carrier approaches its lower limit of movement.
9. In mechanical toys, a load receiving element movable in one direction under the weight of the load, and means for segregating loads for and delivering loads to said element, said means comprising a load run-way, a pivoted gate in said run-way and having its pivot axis extending at right angles to the direction of length of the run-way and located above the path of movement of the load through said run-way, and complementary means carried by the carrier and said gate for moving the gate on its pivot to place it in load-delivering position and retain it in such position while the element is in load-receiving position, said gate having a configuration to act as a load-restraining element at either extreme of its pivotal movement.
10. In mechanical toys, a load carrier movable in one direction under the weight of the load, and means for segregating loads for and delivering loads to said carrier, said means comprising a load run-way, a pivoted gate in said run-way and having its pivot axis extending at right angles to the direction of length of the run-way and located above the path of movement of the load through said run-way, and complementary means carried by the carrier and said gate for moving the gate on its pivot to place it in load-delivering position and retain it in such position while the element is in load-receiving position, said gate having a configuration whereby it will act to prevent escape of the load at one extreme of its pivotal movement and act to segregate the load from the supply and permit its escape when at its other extreme of pivotal movement.
11. In mechanical toys, a load carrier movable in one direction under the weight of the load, and means for segregating loads for and delivering loads to said carrier, said means comprising a load run-way, a pivoted gate in said run-way and having its pivot axis extending at right angles to the direction of length of the run-way and located above the path of movement of the load through said run-way, and complementary means carried by the carrier and said gate for moving the gate on its pivot to place it in load-delivering position and retain it in such position while the element is in load-receiving position, said gate having a configuration curved in the direction of length of the run-way with its pivotal axis located to cause the gate to prevent escape of the load when the gate is at one extreme of its pivotal movement, the movement of the gate by the carrier rocking the gate to segregate such load from the supply and release the segregated load to the carrier.

12. In a mechanical toy and in combination, a load supply structure for fixed loads, a load-delivery chute having one end gate-controlled, a load run-way connecting the supply with the chute, said run-way meeting the chute at substantially right angles to provide load delivery therefrom in directions to intersect the chute direction of length, whereby the loads in the chute will 10 be substantially free from the pressure of

the supply and run-way loads, and a load-receiving element adapted to operate the gate control to release the chute loads one by one.

In testimony whereof I affix my signature in presence of two witnesses.
